Co-pending U.S. Appl. No. 29/586,274, filed Dec. 1, 2016.

Primary Examiner — Prabhakar Deshmukh

(74) Attorney, Agent, or Firm — Wilson Sonsini Goodrich & Rosati

(57) **CLAIM**

The ornamental design for a gaming system controller with mount, as shown and described.

DESCRIPTION

FIG. 1 is a front perspective view of a gaming system controller with mount, showing our new design;

FIG. 2 is a front elevational view thereof;

FIG. 3 is a rear elevational view thereof;

FIG. 4 is a left devotional view thereof;

FIG. 5 is a right elevational view thereof;

FIG. 6 is a top plan view thereof; and,

FIG. 7 is a bottom plan view thereof.

The broken lines in the drawings represent portions of the gaming system controller with mount that form no part of the claimed design.

1 Claim, 7 Drawing Sheets
